(57) **CLAIM**

We claim the ornamental design for a projectile, as shown and described.

DESCRIPTION

FIG. 1 is an isometric view of a third embodiment of our design for a projectile;

FIG. 2 is a top view of the design for the projectile shown in FIG. 1;

FIG. 3 is a right side view of the design for the projectile shown in FIG. 1, the left side view being a mirror image thereof;

FIG. 4 is a bottom view of the design for the projectile shown in FIG. 1;

FIG. 5 is a front end view of the design for the projectile shown in FIG. 1; and,

FIG. 6 is a rear end view of the design for the projectile shown in FIG. 1.

The broken lines are for illustrative purposes only and form no part of the claimed design.
